[57] CLAIM

The ornamental design for a motorboat, as shown and described.

DESCRIPTION

FIG. 1 is a perspective view of a motor boat showing my new design;

FIG. 2 is a top plan view thereof;

FIG. 3 is a right side elevational view thereof, the left side elevational view being a mirror image of that shown;

FIG. 4 is a bottom plan view thereof;

FIG. 5 is a front elevational view thereof;

FIG. 6 is a rear elevational view thereof;

FIG. 7 is a perspective view of a motor boat showing a second embodiment;

FIG. 8 is a top plan view of FIG. 7;

FIG. 9 is a right side elevational view of FIG. 7, the left side elevational view being a mirror image of that shown;

FIG. 10 is a bottom plan view of FIG. 7;

FIG. 11 is a front elevational view of FIG. 7;

FIG. 12 is a rear elevational view of FIG. 7.
